UNITED STATES PATENT OFFICE.

FRANCIS W. OBENHAUS, OF PASADENA, CALIFORNIA.

ELECTRICALLY-OPERATED VALVE.

1,199,298.

Specification of Letters Patent. Patented Sept. 26, 1916.

Application filed October 23, 1915. Serial No. 57,612.

To all whom it may concern:

Be it known that I, FRANCIS W. OBENHAUS, a citizen of the United States, residing at Pasadena, in the county of Los Angeles and State of California, have invented a new and useful Electrically-Operated Valve, of which the following is a specification.

My invention relates to valves, and the principal object of the invention is to provide a valve which can be opened or closed at a distance from the operator by means of electricity transmitted over suitable wires.

A further object of my invention is to provide a valve in which the electro-magnets used are protected both against external injury and against the action of the fluid passing through the valve.

A still further object of my invention is to provide a valve which will have but two working parts and in which it will not be necessary to use any stuffing box for operating the internal mechanism.

Referring to the drawings, which are for illustrative purposes only: Figure 1 is a sectional elevation of a preferred embodiment of my invention with the valve in the open position. Fig. 2 is a partial section showing the valve in closed position. Fig. 3 is a section on the plane x^3-x^3 of Fig. 1, looking in the direction of the arrows. Fig. 4 is a section on the plane x^3-x^3 of Fig. 1, looking in the direction opposite to the arrows. Fig. 5 is a diagram of connections.

In the embodiment of my invention shown in the drawings, a valve body 11 is provided, this valve body being threaded at 12 to receive an inlet pipe, and threaded at 13 to receive an outlet pipe. A diaphragm 14 divides the interior of the valve body into an inlet chamber 15 and an outlet chamber 16. The diaphragm 14 has a horizontal portion 17 through which a vertical opening 18 passes, the opening 18 connecting the chambers 15 and 16 and being surrounded by a seat 19 formed on the upper face of the horizontal portion 17 of the diaphragm 14. A cylindrical opening 20 is cut in the upper portion of the valve body 11, and a clapper 21 slides freely therein, this clapper being preferably formed of iron or steel and having a central slot 22 formed in the upper portion thereof. A horizontal hole 23 is centrally drilled through the clapper 21, this hole 23 being connected to the slot 22 by a vertical hole 24. A small vertical groove 25 is cut in the side of the slot 22 to accommodate a latch pivot 26, this latch pivot being cylindrical in form and consisting of two limbs at right angles to each other, one limb 27 being horizontal and the other limb 28 being vertical and being secured in a horizontal partition 29 formed in a cap 35. Pivoted on the horizontal limb 27 is a latch 30, this latch having a latch pin 31 secured therein. The latch pin 31 is of sufficient length to extend through the hole 24 into the hole 23 and has a shoulder 32 formed thereon so placed that it engages the shoulder formed by the junction of the hole 24 with the hole 23, as shown in Fig. 1, the limb 27 being so located in the latch 30 that the action of gravity tends to throw the latch 30 into the engaged position, as shown in Fig. 1. The latch 30 may be made of magnetic material, or it may have an insert 33 of magnetic material secured therein, for the purposes which will hereinafter be described. The cap 35 is threaded to the valve body 11, as shown at 36, and has an upwardly projecting rim 37 in which an insulating shell 38 is threaded. Three electro-magnets 40, 41 and 42 are wound on cores 43, 44 and 45, these cores being of steel, or other magnetic material, and being secured in the partition 29, projecting slightly therethrough in such a position that they can act upon the clapper 21 and upon the magnetic material 33. The cores 43 and 44 are joined at their upper end by a strip of magnetic material 46, the magnets 40 and 41 with their cores 43 and 44 and the strip 46 forming what is virtually a single lifting magnet, the cores 43 and 44 projecting through the partition 29 in such a position that they act upon and lift the clapper 21. The magnet 42 and the core 45 form what is virtually a releasing magnet, the core 45 projecting through the partition 29 in such a position that it can attract the body of magnetic material 33, lifting the latch 30 into the position shown in Fig. 2 and releasing the shoulder 32 so that the clapper 21 can fall. Three wires 50, 51 and 52 are brought out through the shell 38, these wires being connected as shown in Fig. 5, the wire 52 connecting one side of a battery 53 with the common junction point of the magnets 40, 41 and 42. The other terminals of the magnets 40 and 41 are connected together and are connected through the wire 50 with one contact 54 of a switch

55. The other terminal of the magnet 42 is connected through the wire 51 with a contact 56 of the switch 55. An operating arm 57 of the switch 55 is connected to the other 5 terminal of the battery 53.

The method of operation of the invention is as follows: The valve being closed, as shown in Fig. 2, fluid pressure through the opening 12 acts on the clapper 21 tending 10 to hold it on its seat 19 and prevent any flow of fluid therethrough. The clapper 21 is slightly loose in the cylindrical opening 20 so that it can find its own seat, thereby insuring a tight contact therewith. Whenever 15 it is desired to open the valve, the operating arm 57 of the switch 55 is moved over until it touches the contact 54 and a circuit is maintained from the battery 53 through the arm 57 and the contact 54, 20 through the wire 50, through the magnets 40 and 41, and through the wire 52 back to the battery. The flow of current to the magnets 40 and 41 energizes the cores 43 and 44 and attracts and pulls up the clapper 21 25 which assumes the position shown in Fig. 1. As the magnet 42 is not energized, the weight of the latch 30 forces the shoulder 32 into engagement as shown in Fig. 1, and the valve will remain open even after the 30 switch arm 57 is moved to the off position, as shown in the diagram. This enables the valve to be opened instantly, and provides for its being held open without the necessity for maintaining a constant current in 35 the cores during such a time as it is desired to hold it open. This results in a small current consumption and long life to the battery, and enables the magnets to be heavily energized without danger of overheating 40 them, as the current is only maintained on them momentarily. Whenever it is desired to close the valve the arm 57 is moved over to the contact 56, current flowing from the battery 53 through the arm 57, through the 45 contact 56, through the wire 51, through the magnet 42, and through the wire 52 back to the battery 53. The energizing of the magnet 42 energizes the core 45, the magnetism of which acting on the magnetic 50 material 33 of the latch 30 pulls the latch up into the position shown in Fig. 2, releasing the clapper 21 which drops into the position shown in that figure, thereby closing the opening 18.

55. It is to be especially noted that the magnets 40, 41 and 42 are in a separate chamber from the clapper 21 and that by allowing the cores 43, 44 and 45 to project through

the disk 29, which is of nonmagnetic material, it is possible to operate the internal 60 portions of the valve without the necessity of using stuffing boxes of any kind. It is also to be noted that the pressure of the fluid itself tends to hold the clapper in place when the valve is closed, and that there are 65 only two moving parts, both of which are operated by gravity, so that there is no likelihood of their getting out of order. It is further to be noted that the valve body 11 is of a standard form which is well 70 known in the art and which has proven the most satisfactory for the purposes for which it is used in this invention. It is also to be noted that the magnets 40, 41 and 42, and the cores 43, 44 and 45 may be of practically 75 identical construction, and that this construction is a relatively simple and cheap one.

I find that it is practicable to substitute for the battery 53 any source of direct or 80 alternating current, my invention working equally well on either sort of current.

I claim as my invention:—

In a valve, a valve body, a central diaphragm dividing the interior of said body 85 into an inlet opening and an outlet opening, said diaphragm having an approximately horizontal portion with a vertical opening therethrough which connects said outlet and inlet openings, said inlet opening 90 extending over the horizontal portion of the diaphragm and said outlet opening extending under the horizontal portion of said diaphragm, a seat formed on the upper side of said horizontal portion of said diaphragm 95 around said vertical opening, a clapper sliding in a cylindrical opening formed in the upper part of said valve body concentric with said vertical opening in said diaphragm and so formed that it makes a tight 100 joint with said seat in its lowest position, an imperforate cap tightly closing the top of said cylindrical opening, electro-magnetic lifting means carried on said cap for lifting said clapper, latch means carried on said 105 cap for holding said clapper in the raised position, electromagnetic releasing means for releasing said latch means, and a shell so shaped as to cover and protect said electromagnetic lifting means and said electromagnetic releasing means, said shell being threaded on the upper portion of said cap.

In testimony whereof, I have hereunto set my hand at Los Angeles, California, this 14th day of October, 1915.

FRANCIS W. OBENHAUS.
